UNITED STATES PATENT OFFICE

161,552

LATHE CHUCK

Arthur Merrick Stoner, West Hartford, Conn.,
and Peter Muller-Munk, Pittsburgh, Pa.

Application June 24, 1949, Serial No. 3,524

Term of patent 14 years

(Cl. D54—14)

To all whom it may concern:

Be it known that Arthur Merrick Stoner and Peter Muller-Munk, citizens of the United States of America, residing respectively at 1 Walbridge Road, West Hartford, county of Hartford, State of Connecticut, and at 1209 Wightman St., Pittsburgh, in the county of Allegheny and State of Pennsylvania, have invented a new, original, and ornamental Design for Lathe Chuck, of which the following is a specification, reference being had to the accompanying drawing, forming part thereof.

This is a continuation-in-part of my earlier filed application D. 146,978, filed June 15, 1948, now abandoned.

Fig. 1 is a perspective view; and

Fig. 2 is a side elevation, partly in section, of a lathe chuck, showing our new design.

We claim:

The ornamental design for a lathe chuck, as shown.

ARTHUR MERRICK STONER.
PETER MULLER-MUNK.
